BLOWOUT PREVENTER

John W. MacClatchie, Newhall, Calif., assignor
to MacClatchie Manufacturing Company of
California, Compton, Calif., a corporation of
California

Application May 19, 1937, Serial No. 143,477

4 Claims. (Cl. 166—15)

This invention relates to a blowout preventer and particularly to that type of blowout preventer disclosed in my copending application Serial No. 71,632, filed March 30, 1936, in which co-operating closure elements are adapted to be relatively radially contracted around a well stem such as a drill pipe, or square kelly, or the cooperating closure elements may be relatively radially expanded to clear the bore of the well casing.

10 In the invention described in my above mentioned application, the packing of the cooperating closure elements is adapted for pressure responsive expansible distortion after the closure elements have been relatively radially contracted around a well stem whereby the packing seals tightly around the well stem even though the latter is non-circular in cross-section, e. g. a square kelly.

An object of my invention is to provide a structure which is adapted to receive a drill stem which is non-circular in cross-section, which permits the usual operation of the drill stem, which is adapted to seal off against the drill stem, and against which structure cooperating closure elements are adapted to be relatively radially contractible. The advantage of such a structure is that the cooperating closure elements are enabled to effect a tight seal without subjecting the packing material of the closure elements to the amount of expansible distortion required without the use of such a structure to seal off against a non-circular drill stem as described in my above mentioned copending application.

It is a further object of my invention to provide a structure which is adapted to be mounted in the opening of the housing which is adapted to receive the drill stem and which consists of a non-rotatable member and a rotatable member mounted in said non-rotatable member, and in which the rotatable member has a non-circular bore, formed in part of packing material, which is adapted to receive the non-circular drill stem and which is adapted to permit the usual operation of the drill stem, such as vertical and rotational movement therethrough.

Still another object of my invention is to provide a means of sealing off between the rotatable member and the drill stem.

Still another object of my invention is to mount the rotatable member on anti-frictional bearings in the non-rotatable member and to also provide a means of sealing off between the non-rotatable member and the rotatable member.

Other and further objects and advantages of my invention will be apparent from the follow-

ing specification and by reference to the accompanying drawing, in which an example of the invention is shown, and wherein;

Figure 1 is an elevational sectional view of the blowout-preventer, showing the blowout preventer 5 in operative position.

Figure 2 is a section taken on the line 2—2 of Figure 1.

Figure 3 is a section taken on the line 3—3 of Figure 2. 10

The blowout preventer is incorporated in a string of well casing 1 which is adapted to receive a well stem shown in the present instance as a usual kelly 2; and the blowout preventer comprises cooperating closure elements 3 which are 15 adapted for relative radial contraction around a structure for the well stem as shown in Figures 1 and 2, or relative radial expansion to clear the bore of the well casing. The closure elements project radially from a housing 5 which is connected to proximate lengths of the string of well casing 1 and which has a bore 6 forming a prolongation of the bore 7 of the well casing. The structure against which the closure elements 3 are adapted to pack-off, and through which the 20 non-circular drill stem is adapted to extend is mounted in the bore 6 of the housing 5. The housing 5 is provided with an internal flange 8 which extends into the bore 6. Rigidly but 25 removably secured to said flange 8 is a bearing 30 flange 10.

As shown in Figure 3, attached to the bearing flange 10 by means of screws 11 is an annular non-rotatable member 12, the lower portion of which is provided with a shoulder 13. A rotatable 35 retaining means which is adapted to be rotated with a non-circular drill stem is adapted to be anti-frictionally mounted in the non-rotatable member 12.

As an instance of this arrangement the rotatable retaining means may consist of an annular bearing retaining member 14, having a recess 15, and a shoulder 16, packing gland nut 17, packing gland washers 18 and 19, and packing 20.

The packing gland washer 19 may be provided 45 with a shoulder 21 which is adapted for engagement with the shoulder 16 of the bearing retaining member 14 and thereby prevents any downward movement of the packing washer 19.

In order to provide for both end and lateral 50 thrust and thereby insure operation with a minimum of frictional resistance, ball bearings 22 are provided between the shoulder 10 and the bearing retaining member 14, ball bearings 23 between the bearing retaining member 14 and 55

the shoulder 13 of non-rotatable member 12, and roller bearings 27 are provided in the recess 15 between the non-rotatable member 12 and the bearing retaining member 14.

6 The packing which is provided between the lower end of the non-rotatable member 12 and the packing gland washer 19 for preventing escape of well pressure is so arranged as not to obstruct free rotational movement of the rotatable retaining means with relation to the non-rotatable members and for this purpose the lower part of the non-rotatable member 12 may be recessed as indicated at 28 for the reception of a ring of inverted U packing 29. The inverted 15 U packing 29 is mounted in the recess 28 with the interior of the ring open to well pressure from the bore 7 of the casing by means of an opening 30 in the lower end of the member 12, so that the packing may be operatively expanded 20 for packing off between the lower end of the member 12 and the packing gland washer 19. The packing 29 is also designed to prevent drainage from the space surrounding the bearings 25, 26, and 27 so as to seal against the escape 25 of a lubricant which may be supplied to said space for lubricating the bearings, and a packing ring 31 is preferably secured to the bearing flange 10 and packs off against the packing gland nut 17 for similarly seating the opposite 30 end of the space for the lubricants.

The packing gland nut 17 and the packing gland washers 18 and 19 may be of any suitable wear resisting material such as a suitable metal. The packing 20 may be of any resilient 35 material such as rubber and is designed to permit the usual operation of the kelly. For convenience, the packing may be in the form of a plurality of washers with non-circular bores. The packing gland washers 18 and 19 and the 40 packing 20 are provided with non-circular bores which are only slightly larger than the dimensions of the non-circular drill stem, and are preferably split so that they may be readily mounted on said drill stem.

45 The packing gland nut 17 is threaded into the bearing retaining member 14 as indicated at 32 and is adapted to be tightened by a suitable wrench against the packing gland nut 18, thereby squeezing and expanding the packing 20 and 50 effecting a tight seal between the bearing retaining member 14 and the non-circular drill stem 2.

When it is desired to add another length of 55 drill pipe to the drill string, the screws securing the bearing flange 10 to the internal flange 8 are removed. The kelly may be then raised carrying with it the bearing flange 10, the non-rotatable member 12 and the rotatable retaining means contained therein. After the additional drill 60 pipe has been added to the drill string the kelly carrying with it the bearing flange 10, the non-rotatable member 12 and the rotatable retaining means is again lowered into the housing 5 and 65 reassembled as described hereinabove.

65 The closure elements 3 may be reciprocated in cylinders 4 to provide for their relative radial expansion or contraction, the cylinders projecting radially from the housing 5. The cylinders 4 open into the bore 6 and are equidistantly circumferentially spaced around the housing 5. In the present instance the cooperating closure elements are three in number, and therefore the housing 5 is formed with three of the radially projecting cylinders 4, though any convenient 70 plurality of closure elements may be used.

The closure element in each cylinder 4 comprises a packing cup 40 and one or more cooperating abutment plates 41. The abutment plates prevent distortion of the packing cups longitudinally of the bore 6 when the closure elements 5 are relatively radially contracted around the non-rotatable member 12, and since this distortion may be in either of opposite directions, an abutment plate 41 is preferably provided both above and below the cup 40 as shown at Fig. 1. When 10 the closure elements are relatively radially contracted around the non-rotatable member 12, the abutment plates 41 above the packing cups cooperate to define a closure means in the annular space between the non-rotatable member 15 12 and the wall of the bore 6 for preventing upward distortion of the packing cups, and the abutment plates 41 below the packing cups similarly cooperate to define a closure means in said annular space for preventing downward distortion 20 of the packing cups of the well casing.

Each packing cup 40 is adapted for pressure responsive shifting along its cylinder 4 until relative radial contraction of the closure elements around the non-rotatable member 12 effects a 25 closure means in the annular space between the non-rotatable member 12 and the wall of the bore 6, and shifting of the closure elements being then arrested, the fluid pressure expands and distorts the bottoms 40a of the packing cups 30 so as to seal tightly around the non-rotatable member 12. For this purpose each packing cup is of yieldable material and is preferably resilient, e. g. rubber or the like, and is preferably a deep cup, the wall 40b of which fits snugly in 35 the bore of cylinder 4 with the wall preferably tapering to a thin lip 40c, and with the bottom 40a of the cup of appreciable thickness and having an outer surface tapered as shown at 40d, with an arcuate recess 40e at the apex of the 40 taper and having its axis parallel to the axis of the bore 6.

Fluid pressure in the cylinders 4 in back of the packing cups seals the walls of the cups against the cylinder walls and then shifts the 45 cups in their cylinders until the tapering surfaces 40d of next adjacent cups abut, the angles of the surfaces 40d being such that these surfaces of the plurality of cups will abut when the packing cups have formed a complete closure around the non-rotatable member 12; and the arcuate recesses 40e of the plurality of cups are arranged so as to cooperate to define a bore at the axis of the housing 5 when the packing 50 cups have been projected to operative position, with this bore of a size to receive the non-rotatable member 12. When the cup packings have been thus operatively projected and their movement has been arrested by abutment of their surfaces 40d, fluid pressure in the cups distorts 55 and expands the bottoms of the cups in order to tightly seal the packing cups around the non-rotatable member 12.

The abutment plates 41 are shown as partially encircling the upper and lower portions of 60 the peripheries of the packing cups, and are adapted for retraction and projection with the cups. For this purpose the upper and lower portions of the peripheries of the packing cups are arcuately recessed for some appreciable distance 65 from the bottoms of the cups along their axial length, and the plates 41 are arcuate plates received in said recesses with the outer peripheries of the plates prolonging the peripheral working 70 surfaces of the pistons which are formed by the 75

cup packings. The outer ends of the plates 41 taper as shown at 41d and are recessed to correspond to the taper 40d and the recesses 40e of the packing cups. The plates 41 may be secured to the cup packings for reciprocation therewith, by providing the inner ends of the plates with internal flanges 42 which are received in arcuate slots 43 in the packing cups.

When the packing cups are shifted in their cylinders to operative position, the plates 41 are thus also operatively projected, and when the surfaces 40d of the packing cups abut, the surfaces 41d of the plates 41 similarly abut for arresting further relative radial contraction of the closure elements while permitting expansible distortion of the bottoms of the cup packings to complete the seal as previously described. In practice the arcuate recesses 40e of the packing cup and of the abutment plates are preferably of such depth that when the closure elements are relatively radially contracted around the non-rotatable member 12, the bore which is defined by said recesses, prior to expansible distortion of the bottoms 40a of the packing cups, is very slightly larger than the circumference of the non-rotatable member 12. The expansible distortion to which the bottoms 40a of the cup packings 40 are then subjected closes this space so that the packing seals tightly around the annular member 12 with the small space which still remains between the plates 41 and the annular member 12 of such restricted area that the plates 41 will effectively prevent excessive distortion of the packing vertically in the bore 6.

Means are provided for retracting the closure elements within their cylinders so as to relatively radially expand them from their operative position, and said means is preferably fluid operated.

As an instance of this arrangement a cover plate 44 for the outer end of each of the cylinders 4 may have a depending extension 44a forming a cover plate for a cylinder 45 which is fixed to the cover plate so as to extend parallel to the overlying cylinder 4, and a piston 46 is adapted for reciprocation in each of the cylinders 45. At each of the cooperating cylinders 4-45, a lever 48a is medially pivoted to a supporting arm 47 which may project from the cover plate 44-44a, and one end of this lever is connected to a rod 48 which is connected to the closure element 3, and the opposite end of the lever is connected to a piston rod 49 which is secured to the piston 46. When fluid pressure is supplied to the cylinder 4 and exhausted from the cylinder 45, the closure element 3 is thus shifted in its cylinder to its operative position, thereby retracting the piston 46 in its cylinder 45 and when fluid pressure is exhausted from the cylinder 4 and is supplied to the cylinder 45, the piston 46 is projected, thereby retracting the closure element 3.

A flexible connection is preferably provided between the rod 48 and the closure element 3, whereby the rod retracts the closure element when the piston 46 is projected; but when the closure element is shifted to operative position responsive to fluid pressure in the cylinder 4, the packing cup of the closure element may distort relative to the rod 48 so as to permit sealing engagement by the packing cup with the wall of the cylinder 4 and around the non-rotatable member 12, without strain on the rod 48. As an instance of this arrangement a spider 50 may be fixed to the rod 48, with its periphery comprising a plurality of circumferentially spaced arcuate

members 51, and the members 51 are slotted for reception of tongues 52 of arcuate members 53 which are adapted for reception in arcuate grooves 54 in the inner peripheral surface of the side wall 40b of the packing cup. This connection secures the packing cup 40 and the rod 48 against relative longitudinal displacement for retracting the packing cup when the rod is retracted, but permits radial displacement of the side wall 40b of the packing cup with relation to the rod 48, so that when the packing cup is operatively projected responsive to fluid pressure, the pressure may radially distort the cup with relation to the rod 48 in order to insure an effective seal, without transmitting strain to the rod 48.

Means are provided for substantially simultaneously supplying fluid pressure to the plurality of cylinders 4 and exhausting the plurality of cylinders 45, or exhausting the plurality of cylinders 4 and supplying fluid pressure to the plurality of cylinders 45. As an instance of this arrangement a manifold 60 may extend around the housing 6 below the cylinders 4 and radially inwardly from the cylinders 45, and the manifold may be provided with a pair of conduits 61-62. Below each of the cylinders 4 a pair of conduits 63-64 extend parallel to said cylinder, with the inner ends of said conduits communicating respectively with the conduits 61-62. The outer ends of each of the said conduits 63 opens into its cooperating cylinder 4 as shown at 65 and each of the conduits 64 opens into its cooperating cylinder 45 as shown at 66, and when fluid pressure is exhausted from the cylinders 4, the fluid preferably drains through the conduits 63 into the conduit 61.

When fluid pressure is supplied to the conduit 61 and the conduit 62 is open to the atmosphere, the closure elements 3 are thus shifted to operative position; and when fluid pressure is supplied to the conduit 62 and the conduit 61 is open to the atmosphere, the pistons 46 retract the closure elements 3 to their inoperative position. Pipes 67-68 may be connected to the conduits 61-62 for supplying and exhausting fluid pressure, and a valvular control 69, which may be remote from the blowout preventer, is preferably connected to the pipes, and is preferably arranged so that movement thereof in one direction supplies fluid pressure to the conduit 61 and exhausts the conduit 62, while movement of the valvular control in the opposite direction exhausts the conduit 61 and supplies fluid pressure to the conduit 62.

For this purpose the valvular control is shown as a plug valve, the casing of which has an inlet port 70 connected to a source of fluid pressure, a port 71 which may open to the atmosphere, and a pair of ports 72-73 connected to the pipe 60 67-68 respectively.

The plug of the valve has passageways 74-75 arranged so that when the plug is turned to the position shown at Fig. 2 the pipe 68 exhausts to the atmosphere and the pipe 67 is open to the fluid pressure supply, and when turned ninety degrees the pipe 68 is open to the fluid pressure supply and the pipe 67 exhausts to the atmosphere.

In operation the annular space between the non-rotatable member 12 and the bore 6 of the housing is unobstructed as long as the closure elements 3 occupy their inoperative position.

When it is desired to seal off around the non-rotatable member 12, for example when a blow-

out occurs or when the well is to be kept under control, fluid is exhausted from the cylinders 45 and fluid pressure is supplied to the cylinders 4 for projecting the closure elements to their operative position; with movement of the closure elements arrested by abutment of the surfaces 40d—41d of the cooperating closure elements. Continued fluid pressure exerted against the cup packings then expansively radially distorts the bottoms 48a of the cups so that they seal around the non-rotatable member 12, with the abutment plates 41 preventing distortion of the packing cups vertically of the bore 6. Sufficient pressure may be maintained in the cylinders 4 as 15 will hold the seal against any well pressure liable to be encountered.

In wells in which only low pressures are encountered or by the use of suitable packing material, the abutment plates 41 may be omitted.

20 Although I have described my invention in connection with the use of three cooperating closure elements, excellent results can be obtained by the use of two, or any other convenient plurality of closure elements.

25 Although I have described my invention with respect to certain particular embodiments thereof, nevertheless I do not desire to be limited to the particular details shown and described except as clearly specified in the appended claims, since 30 many changes, modifications and substitutions may be made without departing from my invention in its broader aspects, which may be found useful in many other applications thereof.

I claim:

35 1. Closure means for a well casing, including a stationary body arranged to be mounted on a well casing, a non-rotatable member arranged for direct vertical movement into and out of said body, a rotatable member in said non-rotatable 40 member and movable vertically therewith, a closure means in said body relatively radially contractible for sealing around said non-rotatable member, the portion of said closure means which is adapted to seal around said non-rotatable 45 member being formed of packing material, and means functioning independently of pressure in the bore for exerting fluid pressure against said portion of said closure means for expansively distorting said packing material for projection 50 against and into sealing engagement with said non-rotatable member.

2. In a blowout preventer, a housing having a bore arranged to be mounted on a well casing, a plurality of cylinders opening into said bore, a non-rotatable member arranged for direct vertical movement into and out of said bore, a 5 rotatable member in said non-rotatable member and adapted to be moved vertically therewith, closure elements in each of said cylinders radially movable into sealing engagement with said non-rotatable member, the portions of the closure 10 elements which are adapted to abut said non-rotatable member being formed of packing material and adapted for expansive distortion into said bore, and means for expansively distorting the packing material for projection into the bore 15 for sealing around said non-rotatable member.

3. Closure means for a well casing, including a stationary body arranged to be mounted on a well casing, a cylindrical non-rotatable member arranged for direct vertical movement into and 20 out of said body, a rotatable member journaled entirely within the cylindrical non-rotatable member, packing between said non-rotatable member and said rotatable member arranged to be expanded by fluid pressure, and closure elements mounted in said stationary body and 25 adapted to be expanded by fluid pressure other than well casing pressure for sealing around said cylindrical non-rotatable member.

4. Closure means for a well casing, including 30 a stationary body arranged to be mounted on a well casing, a cylindrical non-rotatable member arranged for direct vertical movement into and out of said body, a rotatable member adapted to be mounted entirely within said cylindrical non- 35 rotatable member, anti-frictional end and lateral bearing means between the rotatable member and the non-rotatable member, sealing means between the cylindrical non-rotatable member and the rotatable member adapted to be expanded by well pressure, a packing in said rotatable member for engaging and packing off a drill pipe, whereby said members may be bodily raised and lowered into said body by said drill pipe, and closure elements mounted in said stationary 40 body and adapted to be expanded by fluid pressure other than well casing pressure for sealing around said cylindrical non-rotatable member.

JOHN W. MACCLATCHIE. 50
